UNITED STATES PATENT OFFICE.

CHESTER W. CANINE, OF CINCINNATI, OHIO.

CONVEYER DEVICE FOR LAUNDRY ASSORTING AND MARKING BOOTHS.

Application filed February 14, 1921. Serial No. 444,856.

To all whom it may concern:

Be it known that I, CHESTER W. CANINE, a citizen of the United States, and resident of Cincinnati, in the county of Hamilton 5 and State of Ohio, have invented a certain new and useful Conveyer Device for Laundry Assorting and Marking Booths, of which the following is a specification.

In modern laundries there is now usually 10 employed a series of marking and assorting booths, in each of which there is an operator who receives a bundle of laundry and who assorts it and marks each article, wheréupon all of the articles thus assorted and marked 15 in the various booths are sent to the wash room.

For purposes of economical operation of the laundry, it is essential that the bundles be supplied constantly and promptly to the 20 operators in the booths, and also that the assorted and marked laundry articles be promptly delivered from the booths to the wash room.

The objects of my invention are to provide 25 a conveyer device of simple, durable and inexpensive construction, designed to be attached to and form part of the laundry booths, and so arranged that the operators in all of the booths may place their assorted 30 and marked laundry articles upon the conveyer without going out of their booths, and such articles will then be promptly delivered to the wash room.

A further object is to provide improved 35 means in a conveyer of this character, whereby the delivery end of the conveyer may be readily, quickly and easily raised or lowered to deliver the articles into trucks or receptacles of various heights, and also to provide 40 a conveyer device of this character in which articles of various kinds, both light and heavy in weight, may be carried without danger of having them blown off the conveyer, or caught or entangled in any of 45 the parts of the conveyer.

Still a further object is to provide a device of this character in which the same supporting structure for the first mentioned conveyer may also be conveniently and easily 50 employed for a second conveyer for delivering bundles to the operators in the booths.

Still a further object is to provide an improved bundle carrier conveyer and means whereby the conveyer will be automatically

stopped when it has delivered a bundle adjacent to any one of the booths, to thereby prevent bundles becoming lost and being carried beyond the end of the row of booths or past the last booth in which there is an operator at work. 55

My invention consists in the construction, arrangement and combination with a series of booth frames, of a conveyer supporting frame, and the construction of the main laundry conveyer and its adjustable delivery 60 device, and also in the construction, arrangement and combination with such conveyer frame of a bundle conveyer device, and also in the construction of the means for automatically stopping the bundle conveying device, whereby the objects contemplated are 65 attained, as hereinafter more fully set forth, pointed out in my claims, and illustrated in the accompanying drawings, in which:

Figure 1 shows a top or plan view of two 70 adjacent laundry booths, illustrating the manner in which my improved conveyer device is connected therewith.

Figure 2 shows a side elevation of the delivery end of the conveyer device, illustrating 75 the adjustable delivery member.

Figure 3 shows an enlarged detail view 80 illustrating the means for adjusting the tension on the laundry delivery belt.

Figure 4 shows a detail view illustrating 85 the means for driving the conveyer operating shaft from a motor.

Figure 5 shows a longitudinal sectional view of the main conveyer device. The dotted lines show the delivery conveyer 90 member in adjusted or lowered position.

Figure 6 shows a top or plan view of the delivery conveyer member.

Figure 7 shows a detail view illustrating 95 the adjustable support for the delivery conveyer member.

Figure 8 shows a transverse sectional view through the main conveyer frame.

Figure 9 shows a side elevation of the main conveyer frame, with the auxiliary bundle 100 conveyer device connected therewith.

Figure 10 shows a detail sectional view, illustrating the means for automatically stopping the auxiliary bundle conveyer device.

Figure 11 shows a top or plan view of the 105 auxiliary bundle conveyer device, illustrating particularly the means for automatically stopping it; and

Figure 12 shows an end elevation of the main conveyer and the auxiliary bundle conveyer, and illustrating the means for driving the auxiliary conveyer and for automatically stopping it.

Referring to the accompanying drawings, I have used the reference numeral 10 to indicate the structural frames of the assorting and marking booths. Within each booth is 10 a table 11, upon which the operator places the goods to be assorted and marked. The frame of each booth is preferably made of pipes, and I have provided a pipe structure for a conveyer, which also forms a part of 15 the end of the series of booths, which pipe structure comprises a series of upright supporting pipes 12 arranged in line with the upright supporting pipes of the booths, and 20 two spaced-apart longitudinal pipes 13 connected to the upright pipes by the fittings 14.

Extending upwardly from the pipes 13, above the pipes 12, are the pipes 15, which are connected at their tops by the pipes 16, thus forming a rectangular space in which 25 the clothes to be delivered to the wash room are placed by the operators in the booths.

At the receiving end of the conveyer frame are the short pipes 17 connected to the up- 30 rights 12 and the pipes 13 and supported by the upright 18, and between the uprights 18 and 12, at the end, is fixed a frame 19 in which is slidingly supported a roller 20. This roller is made adjustable in the sliding 35 frame by the set screw 21. A similar roller 22 is mounted at the opposite end of the conveyer frame, and the endless flexible conveyer 23 is passed around these rollers, and this flexible conveyer is supported at intermediate points by the rollers 24 mounted between the uprights 12, as shown in Figure 5.

Mounted above the cross pipes 16 is a flat sheet metal top 25, and the outer side of the conveyer receptacle is preferably covered by slats 26, and the inner side is provided with 40 a solid wall 27 having an opening 28 therein at each booth, through which the operator may readily and easily place the laundry articles on the conveyer after they have been marked and assorted. These openings 28 are 45 also preferably arranged close to and on about the same level as the work table 11, so that the marked and assorted laundry articles may simply be slid off the work table through the opening 28, and will then be 50 received upon the traveling endless conveyer 23.

The means for operating the endless conveyer comprises a motor 29, provided with a worm 30 on its shaft, in mesh with a gear 31, which gear is mounted on a shaft 32, and this shaft is provided with a small pulley 33, and this pulley is connected by a belt 34 with a large pulley 35 on the shaft of the roller 22. Adjacent to the pulley 35 is a second pulley 36, to which the belt

37 is applied for the purpose of driving the adjustable delivery conveyer hereinafter described.

In practical use with this part of the apparatus, it will readily be seen that a very firm and durable and economical construction is provided, because the supporting structure for the conveyer is connected with and forms part of the supporting structures for the various booths, and furthermore the arrangement relative to the booths is such that as fast as the articles are assorted and marked on the work tables within the booths, they may simply be slid over the work table through the openings 28 in the side of the 70 conveyer frame, and will then be received upon the conveyer and carried to the delivery end thereof, and the structure is such that these laundry articles, no matter how light or heavy, or how large or small, will be carried to the delivery end, and cannot be blown off or caught or entangled during 75 their progress to the delivery end.

My improved adjustable delivery member for the conveyer comprises a frame having two parallel side pipes 38, to which are attached the upwardly extending side boards 39. At the receiving end of this frame is a cross shaft 40, mounted in suitable bearings on an upright supporting leg 41 of the main 80 conveyer frame. On the outer end of this shaft 40 is a pulley 42, to which the belt 37 is connected for driving it. At the upper 85 end of the frame members 38 is a roller 43, and a conveyer belt 44 is passed around these 90 two rollers.

Slidingly mounted upon the frame members 38 are the T-shaped pipe fittings 45, and these are connected to uprights 46 which are in turn connected to the cross pipe 47 95 which is rotatably mounted in the T-shaped pipe fitting 48, and this latter is provided with a base or upright member 49.

By this arrangement it is obvious that the elevation of the delivery conveyer device 110 may be readily and easily adjusted by simply sliding the supporting member 49 either toward the main conveyer or away from it, as illustrated by dotted lines at the left in Figure 5, and in any position of its adjustment 115 the supporting device will form a firm and rigid support.

In order to prevent clothes from becoming caught or entangled in the sides of the frames between the place where the clothes are delivered from the main conveyer to the adjustable delivery conveyer, I have provided on each side of the main conveyer a segmental plate 50 secured to the main frame at 51 and extending outwardly and 120 downwardly close to the inner surfaces of the side boards 39, and between said side boards and the conveyer belt 44, as shown 125 in Figure 5.

By this construction it will be seen that 130

the delivery conveyer member has its conveyer belt continuously driven during the time that the main conveyer is running, and that the clothes cannot become caught or 5 entangled therein, and that the delivery conveyer may be adjusted to any desired elevation and there firmly held without any support at its outer end, so that the contents thereof may be discharged into trucks 10 or baskets of different heights or sizes.

In some instances it is desirable to also provide for the delivery of bundles from the bundle receiving compartment to the operators of the various booths, and I have 15 provided a conveyer of this kind which may be very easily and quickly applied to my improved device, and may be made to utilize the same frame as the main conveyer, so that an extremely economical construction 20 is provided for this auxiliary bundle conveyer.

When it is desired to employ the auxiliary conveyer, I provide two rollers 52 mounted in suitable brackets 53 at the ends 25 of the main frame. In the accompanying drawings only one of these rollers and brackets is shown, and the bundle conveyer is passed around these two rollers, one part of it going above the top member 25 and 30 the other below, so that the conveyer travels upon the top member 25. The return member is below the top, and may be supported upon rollers 54 mounted between the uprights 15. This conveyer is preferably provided at intervals with slats 55 extended transversely and of considerable height, for 35 engaging the bundles and forcing them against the stop devices hereinafter provided.

For driving the auxiliary bundle conveyer I preferably provide the roller 52 with a detachable clutch member 56, and on the outer end of this clutch member is a 40 large pulley 57 connected by a belt 58 with a small pulley 59 mounted on the shaft of the roller 22, so that this bundle conveyer is thereby driven at a much slower speed 45 than the main laundry conveyer. The receiving end of this auxiliary bundle conveyer is extended to some distant point, where the bundles received in a laundry may 50 be conveniently placed on it, and since these bundles are all relatively heavy, no provision need be made for preventing them 55 from blowing or falling off.

It is, however, desirable that none of 60 these bundles be delivered past the last one of the booths, and it is also desirable that the bundles may be stopped adjacent to any 65 booth desired, and for this purpose I have provided the following mechanism:

Mounted on the main frame of the conveyer, is a series of links 60 extending upwardly and all pivotally connected to a 65 bar 61. This bar is provided on one end

with a downwardly extending arm 62, which arm enters a groove 63 in the movable part of the clutch member 56, so that an outward movement of this arm 62 will disconnect the clutch member 56 and stop 70 the operation of the auxiliary bundle conveyer.

For the purpose of converting a longitudinal movement of the bar 61 to an outward movement of the arm 62, I have provided in the bearing 53 an inclined notch 64, into which the end of the arm 62 is received, and which will cause the arm to be guided outwardly when the bar is moved 75 longitudinally.

For the purpose of automatically throwing the auxiliary bundle conveyer out of operation, I have provided on the bar 61 a series of stop blades 65, pivotally supported 80 so that they may be turned upwardly where they will not interfere with the bundles, or downwardly where they will be engaged by bundles on the bundle conveyer. I preferably provide one of these stop blades adjacent to each booth, and one adjacent to the delivery end. The one adjacent to the delivery end is always in its lowered position, but the others may be raised or lowered by 85 the operators in the booths.

In practical use with this part of the device, the bundles are placed upon the bundle conveyer and then are slowly moved past each of the booths, and the operators in the booths reach out and get new bundles whenever they have finished with the ones they 90 previously have. In the event that a bundle should be carried past the last booth, it will then engage the stop blade 65, and the bundle will be pressed by the cross piece 55 against the blade 65, and will thereby cause 95 the bar 61 to move longitudinally and thus throw the auxiliary conveyer out of gear, and it will remain out of gear until this bundle has been removed by the operator 100 in the last booth. The auxiliary conveyer 110 can then be started by simply moving the bar 61 rearwardly.

In the event, however, that no one occupies the last booth, or the operator in any one of the booths desires to stop all bundles 115 in front of that particular booth, then any one of the various stop blades 65 may be lowered to the position shown in Figure 12, whereupon the auxiliary conveyer will stop 120 when a bundle strikes said stop blade.

I claim as my invention:

1. The combination with a series of laundry marking and assorting booths having frames, of a conveyer frame attached to and forming part of the adjacent booth constructions, an endless conveyer mounted therein, a top member supported on the frame above the conveyer, and a side wall supported on the frame above the conveyer, the side wall adjacent to the booths being 125 130

provided with a series of openings, one for each booth, through which material may be passed from the booths upon the conveyer, for the purposes stated.

2. The combination with a series of laundry marking and assorting booths having frames made of pipe and pipe fitting construction, of a conveyer frame formed of pipe and pipe fitting construction and attached to and forming part of the adjacent booth constructions, an endless conveyer mounted therein, a top member supported on the pipe frame above the conveyer, and a side wall supported on the pipe frame above the conveyer, the side wall adjacent to the booths being provided with a series of openings, one for each booth, through which material may be passed from the booths upon the conveyer, for the purposes stated.

3. The combination with a series of laundry marking and assorting booths having frames made of pipe and pipe fitting construction, of a conveyer frame formed of pipe and pipe fitting construction and attached to and forming part of the adjacent booth constructions, an endless conveyer mounted therein, a top member supported on the pipe frame above the conveyer, a side wall supported on the pipe frame above the conveyer, the side wall adjacent to the booths being provided with a series of openings, one for each booth, through which material may be passed from the booths upon the conveyer, a motor, and a driving mechanism connected with the motor, supported upon the pipe construction below the conveyer and capable of operating the conveyer, for the purposes stated.

4. The combination with a series of laundry marking and assorting booths having frames made of pipe and pipe fitting construction, of a conveyer frame formed of pipe and pipe fitting construction and attached to and forming part of the adjacent booth constructions, an endless conveyer mounted therein, a top member supported on the pipe frame above the conveyer, a side wall supported on the pipe frame above the conveyer, the side wall adjacent to the booths being provided with a series of openings, one for each booth, through which material may be passed from the booths upon the conveyer, two additional pipe uprights at the receiving end of the conveyer frame and spaced from the main frame, brackets attached thereto, the adjacent conveyer roller being slidingly mounted in said brackets, and an adjusting screw supported by the main frame to engage said adjustable roller supports.

5. The combination with a conveyer of the class described, of an adjustable delivery 65 conveyer frame comprising two side mem-

bers, rollers at the ends of the side members, side boards supported on the side members above the conveyer, T-shaped pipe fittings slidingly mounted upon said sliding members, a pipe connecting said T-shaped pipe fittings, an upright rotatably connected with the pipe connecting the T-shaped pipe fittings, and means for pivotally supporting the receiving end of said delivery frame, whereby a movement of the supporting leg toward or from the pivotal end will raise or lower the delivery end and firmly and securely support it in various positions of adjustment. 70 75

6. The combination with a conveyer of
the class described, of an adjustable delivery
conveyer frame comprising two side mem-
bers, rollers at the ends of the side members,
side boards supported on the side members
above the conveyer, T-shaped pipe fittings
slidably mounted upon said sliding mem-
bers, a pipe connecting said T-shaped pipe
fittings, an upright rotatably connected with
the pipe connecting the T-shaped pipe fit-
tings, means for pivotally supporting the re-
ceiving end of said delivery frame, whereby
a movement of the supporting leg toward or
from the pivotal end will raise or lower the
delivery end and firmly and securely sup-
port it in various positions of adjustment, a
segmental shield and blades fixed to a sta-
tionary support at one end and extended be-
tween the said side boards and the side edges
of the conveyer, for the purposes stated. 80
85
90
95

7. In a device of the class described, the combination of a main conveyer frame having a top member, a main conveyer mounted in the frame, an auxiliary bundle conveyer running in one direction above said top, and in the other direction below the top, the frame of the main conveyer being designed to support the auxiliary conveyer, means for driving the main conveyer, means connected therewith and operated thereby for driving the auxiliary conveyer, and means for throwing the auxiliary conveyer into and out of operation without stopping the main conveyer. 100 105 110

8. In a device of the class described, the combination of an endless conveyer having raised cross slats thereon, means for driving it, means for operatively connecting or disconnecting the driving mechanism, a stop blade supported above the conveyer and capable of movement to or from position where it will be engaged by a bundle on the conveyer, and means whereby the bundle on the conveyer engaging said stop blades will throw the conveyer out of operation. 115 120

9. In a device of the class described, the combination of an endless conveyer having raised cross slats thereon, means for driving it, means for operatively connecting or disconnecting the driving mechanism, a stop blade supported above the conveyer and ca- 130

- pable of movement to or from position where it will be engaged by a bundle on the conveyer, and means whereby the bundle on the conveyer engaging said stop blades will 5 throw the conveyer out of operation, said means comprising a clutch member on the driving shaft of the conveyer, and an arm operatively connected with the stop blade, and also with the clutch, and so arranged 10 that when the stop blade is moved toward the delivery end of the conveyer the said arm will throw the clutch to inoperative position, and when moved back will again throw the clutch to an operative position.
- 15 10. In a device of the class described, the combination of an endless conveyer having raised cross slats thereon, means for driving
- it, means for operatively connecting or disconnecting the driving mechanism, a stop blade supported above the conveyer and capable of movement to or from position where it will be engaged by a bundle on the conveyer, means whereby the bundle on the conveyer engaging said stop blades will 20 throw the conveyer out of operation, and a series of stop blades capable of movement from operative positions adjacent to the conveyer, to inoperative positions above the conveyer, and all connected to the said means for throwing the conveyer into and 25 out of operation.
